UNITED STATES PATENT OFFICE.

WILHELM HECKEL, OF BIEBRICH, GERMANY.

CLARINET.

SPECIFICATION forming part of Letters Patent No. 706,557, dated August 12, 1902.

Application filed August 27, 1900. Serial No. 28,242. (No model.)

To all whom it may concern:

Be it known that I, WILHELM HECKEL, a subject of the King of Prussia, German Emperor, and a resident of Biebrich-on-the-Rhine, 5 Province of Hesse-Nassau, German Empire, have invented certain new and useful Improvements in Clarinets, of which the following is an exact specification.

My invention consists in improvements in 10 clarinets in which two octave-holes are opened or kept open by the pressure upon a single-octave key. In the generally-employed instruments belonging to the class of the clarinets—as alt clarinets, bass clarinets, contra- 15 bass clarinets—the octave-key is also used for the “B” key, so that from the same hole the tone “B” is obtained. The arrangement of double openings hitherto known was such that a second hole (octave-hole) was only 20 opened when the octave-key and another key were simultaneously pressed down. It was not known hitherto to arrange the octave-holes in such a manner that the divided air column can freely pass through them, as is 25 the case in my invention.

The purpose of my invention is to obtain 30 absolutely clear duodecims of the clarinet, which purpose is fulfilled by the arrangement hereinafter described, by which means the “E” key presses automatically upon an auxiliary key and opens thus an auxiliary hole.

In the clarinet instruments hitherto employed the duodecims are obtained by the arrangement of a bigger hole through which 35 the air column is pressed and which is arranged underneath the key *a*. If this hole is too small, then the duodecims are still obtained; but the high “C,” as well as the whole high register, is too deep. If the hole 40 is big enough, the high “C” is obtained; but the duodecims, as well as the tones upward from the high “D,” are much too high.

By means of the present invention it is possible to obtain absolutely clear duodecims, 45 since the hole of the auxiliary key compensates for all unevenness of the intonation, because, as already mentioned, the divided air column is allowed to pass freely in two directions and is not forced to pass through one 50 hole.

In order to make my invention more clear, I refer to the accompanying drawings, in which—

Figure 1 shows a front view of a clarinet

with my new arrangement. Fig. 2 is a rear 55 view of the clarinet, showing a part of the mechanism diagrammatically. Fig. 3 is a modified form of construction.

a is an octave-key which is also used for the “B” key. The hole *b* is arranged side- 60 ward upon the clarinet. The arrangement of the levers is already known and not shown on the drawings. By pressing down the key *a* the hole *b* of the clarinet is opened. The key *c* being arranged underneath the key *a* 65 is therefore also pressed down, and consequently the hole *d* is simultaneously opened. The arrangement of the hole *d* in connection with the keys is shown in Fig. 2 out of position for the sake of better comprehension of 70 this arrangement. It will be easily understood that the hole *d* is arranged upon the clarinet on the opposite side of the hole *b*.

In Fig. 3 a modification is shown in which the auxiliary key *c* is not arranged underneath the key *a*, but on the side of the same, so that the player will be able with one finger simultaneously to press down both keys *a* and *c*. Evidently this arrangement is more 80 convenient than the arrangements heretofore described.

Having thus fully described the nature of this invention, what I desire to secure by Letters Patent of the United States, is—

1. A clarinet or like instrument having two 85 octave-holes *b*, *d*, arranged at the same height, *i. e.*, at the same distance from the mouthpiece, and opposite to each other, and means for simultaneously opening and closing said holes. 90

2. A clarinet or like instrument, provided with two octave-holes arranged at the same height, *i. e.*, at the same distance from the mouthpiece, and opposite to each other, in combination with a key adapted when pressed 95 down to open one of said holes, and a second key arranged relatively to the first key, whereby when the latter is pressed down, the said second key will be operated to open the other hole simultaneously. 100

In testimony whereof I have signed my name to this specification in the presence of two subscribing witnesses.

WILHELM HECKEL.
